UNITED STATES PATENT OFFICE.

FRANK D. HAWKINS, OF SIOUX FALLS, SOUTH DAKOTA.

RECOIL PAD.

Application filed November 10, 1924. Serial No. 748,954.

To all whom it may concern:

Be it known that I, FRANK D. HAWKINS, a citizen of the United States, residing at Sioux Falls, in the county of Minnehaha, 5 and State of South Dakota, have invented certain new and useful Improvements in Recoil Pads, of which the following is a specification.

This invention relates to certain new and 10 useful improvements in recoil pads and pertains more particularly to an improvement on my Patent No. 1,325,152 of December 16, 1919.

The primary object of the invention is to 15 provide a pad wherein the longitudinal central portion has a relatively rigid support that affords a line of flexure common to and for the opposed side portions, which latter beyond such line are consequently relatively 20 resilient and are free to flex about the line to take up shocks.

A further object of the invention is to 25 provide a support which strengthens and stiffens the cellular formation of the pad and which affords effective anchorages for the attaching screws, or other similar fastening means.

The invention further aims to provide 30 means of the nature set forth, which closes the cells at their central portions against the passage of air therethrough, and which divides the cells into two separate and distinct divisions.

In the drawings:—

35 Fig. 1 is a side elevation of the rear end of a gun stock with the present invention applied thereto.

Fig. 2 is a view taken on line 2—2 of 40 Fig. 4;

Figs. 3 and 4 are sectional views taken on lines 3—3 and 4—4 respectively of Fig. 1.

In proceeding in accordance with the 45 present invention, the pad is formed of two similar sections, each of which is made of soft rubber and has an inner wall 1, an outer wall 2 and solid end parts 3. The parts of the sections intermediate the ends 3 are connected by webs 7 of zig-zag formation to provide a cellular or truss formation.

50 A longitudinal soft rubber strip 4 is interposed between the inner sides of the sections and is connected thereto, for example by cementing. A rubber sheet 10 is cemented to the inner wall 1 and to the adjacent longitudinal edge of the strip 4 and a simi-

lar although thicker rubber sheet 9 which forms a face plate that rests against the shoulder of the gunner, is cemented to the outer wall 2 and to the adjacent longitudinal edge of the strip 4.

60 The sheet 10 is cemented to a hard rubber base plate 8. The cells are thus closed against the passage of air therethrough and each receives support at its inner end from the strip 4. The strip 4 acts as a stiffener 65 which extends centrally of the width of the pad, and which acts to prevent ready flexure of the outer sides of the cells and plate.

The strip 4 is furthermore formed with 70 perforated enlargements 5 to enable the passage therethrough of fastening screws 6 or the like, the latter extending through registering perforations in the hard rubber base plate 8 and securing the entire device onto the gun stock.

75 The strip 4 further acts to strengthen the truss or cellular formation and to prevent same from breaking down through long or constant use.

What is claimed is:—

80 1. In a rubber recoil pad for gun stocks, a pair of sections each having spaced inner and outer walls, solid end parts connecting the walls, cellular connections between the walls, a central soft rubber strip interposed 85 between the inner sides of the sections and engaged therewith, and inner and outer rubber strips secured to the respective inner and outer walls and to the inner and outer longitudinal edges of the central strip. 90

2. In a rubber recoil pad for gun stocks, spaced inner and outer walls, cellular connections between the walls, and a rubber strip extending longitudinally of the walls and central of the width thereof so as to 95 provide a stiffening means resisting flexure of the parts of the cells adjacent the strip while permitting flexure of the remaining parts of the cells.

3. In a rubber recoil pad, a cellular rubber body, and a longitudinal rubber strip in the body disposed central of the width thereof to resist flexure of the inner parts of the cells and to allow of flexure of the outer parts thereof and to close the cells 100 against the passage of air therethrough.

4. In a recoil pad for gun stocks, a rubber body having spaced inner and outer walls, means to flexibly connect the walls, and means disposed longitudinally of the 105

walls and central of the width thereof for resisting flexure of the connecting means adjacent to said second means while permitting flexure of the remainder of the connecting means.

5. In a recoil pad for gun stocks, a cellular rubber body, and means extending lon-

gitudinally of the body and between the sides thereof to resist flexure of the inner parts of the cells while permitting flexure of the outer parts thereof and to prevent the passage of air through the cells.

In testimony whereof I affix my signature
FRANK D. HAWKINS.
